Inventor:

Abe Jaffe,

By Attorney.

UNITED STATES PATENT OFFICE.

ABE JAFFE, OF PHILADELPHIA, PENNSYLVANIA.

NECKTIE HOLDER.

Application filed December 15, 1926. Serial No. 154,995.

My invention relates to a new and useful necktie holder, and it relates more particularly to a necktie holder and retainer adapted for the type of ties which are pre-formed and permanently tied, having opposed lateral wings which are positioned under the collar.

The object of my invention is to provide a necktie holder which will be firmly and permanently attached to the necktie, and which is adapted to engage the head of the front collar button in a secure manner, so as to retain the necktie in position and to prevent the same from working loose accidentally.

By my novel construction, moreover, a more compact arrangement of the operative or moving elements of the necktie holder is obtainable, and the assembling of the device is simplified and facilitated.

With the above ends in view, my invention consists of a metallic base plate having opposed and laterally extending wing portions corresponding to the wings of the necktie, and a central pendant portion corresponding to the knot of the necktie; said metallic base plate being adapted to be embedded or encased within the wing and knot portions of the necktie. My invention further consists in the provision of an aperture in the central portion of said base plate, adapted to receive the head of the front collar button, and a spring operable bolt member slidably mounted upon said central portion of the base plate, beneath and in operative alignment with said aperture and adapted to coact therewith firmly and securely to engage the head of the collar button and thereby to retain in position the necktie. The sliding bolt is manually operable to release the device from the button and the button may be inserted either after manually retracting the slide or the pressure of the button during insertion will retract the slide.

My invention further consists of other novel features of construction described more in detail hereinafter and shown more particularly in the accompanying drawings.

In the accompanying drawings in which like reference characters indicate like parts:

Fig. 1 represents a front elevation of a preformed and permanently tied necktie, having embedded therein, or attached thereto, a necktie holder embodying my invention; Fig. 2 is a similar front elevation of my novel necktie holder, shown detached from

the necktie; Fig. 3 represents a vertical section on the line 3—3 of Fig. 1.

In the embodiment of my invention shown in the accompanying drawings, the sheet metal base plate 1, of suitable thickness or gauge, forms the two laterally opposed wings 2 and 3, and the central pendant portion 4 corresponding to the knot of the finished necktie.

A substantially rectangular aperture 5 is provided along the vertical median line of the central portion 4, of the base plate 1, at a height corresponding to the position of the front collar button 6, and adapted to receive the head thereof, in a manner shown particularly in Fig. 3. The collar button receiving aperture 5, is formed by providing two downwardly converging or V shaped cuts 7 and 8 and a lower horizontal cut 9, and bending outwardly an upper triangular spring support 10, and the two vertical guide members 11 and 12.

Directly below and in vertical alignment with the aperture 5, I provide two opposed vertical guides 13 and 14, preferably formed by pressing out corresponding portions of the body of the sheet metal. A spring bolt or slide 15 is slidably mounted between the two guides 13 and 14. An upper transverse clamping head 16 is carried at the top of the slide 15 which is guided between the two vertical guide members 11 and 12. The lower end of the slide 15 is bent outwardly at a right angle to the same, so as to form a hook 17, to which the lower end of a helical tension spring 18 may be attached. A corresponding upper stationary hook 19 is formed on the apex of the triangular member 10. The attachment of the two ends of the spring 18 to the two hooks 17 and 19, tends to draw the slide 15 upwardly.

Upon inserting the head of the collar button 6 into the aperture 5, the triangular spring member 10 tends to divert the button head downward and causes it to press down the slide sufficiently for the passage of the head through the aperture. When the head has cleared the edge of the slide, the spring draws the slide up against the button shank 105 and locks the head against the upper triangular spring member 10, as indicated in Fig. 3.

In order to facilitate the manual withdrawal of the slide 15, while attaching or detaching the necktie holder to or from the collar button 6, a lower pendant manually

operable pull rod or handle 20 may be provided in a manner shown particularly in Figs. 2 and 3. The rod 20 is secured to the lower lateral hook member 17, and may be guided by a suitable vertical guide member 21 which may also be pressed out of the body of the sheet metal, as indicated in Fig. 2. By means of the pull rod or handle 20, the slide 15 is operable with ease and facility.

In order to facilitate the attachment of the necktie holder to the necktie 22, a stitch aperture or slot 23 may be provided at the top of the base plate 1 and suitable cuts 24 and 25 may also be provided for receiving suitable stitches whereby the fabric of the necktie knot may be secured to the metallic base plate of my novel necktie holder.

A pair of opposed knot retaining members 26 and 27 may also be provided near the lower end of the central knot portion 4 of the base plate 1, preferably formed integrally with said base plate, in a manner shown particularly in Figs. 2 and 3. By enclosing the lower portion of the inner knot filling of the necktie, within the members 26 and 27, the knot of the necktie is held in a central and orderly position at all times.

In order that the slide 15 shall not come in contact with the fabric or filling of the knot of the necktie 22, a suitable metallic shield 28 may be secured to the base plate portion 4, surrounding the slide 15 as well as the spring 18 and the corresponding guide and hooks. The shield may be secured by any suitable means, as by soldering or by means of suitable tongues and apertures, or the like.

In the finished form of the necktie, the base plate 1, including the wings 2 and 3 as well as the knot portion 4, will be encased within, or attached to the corresponding portions of the necktie, with the operative parts, such as the aperture 5 and the pull rod 20 exposed. Thus the necktie holder of my novel construction will not detract from the appearance of the necktie, but, on the contrary, will aid in maintaining its shape.

Having described my invention, I claim:

1. A necktie holder comprising a sheet body portion, containing a button receiving aperture, an upright slide mounted upon said body, below and in vertical alignment with said aperture and adapted to engage behind the head of a collar button inserted into said aperture, said body having a spring anchorage above said aperture, and a helical

tension spring operatively interposed between said anchorage and said slide to draw the latter upwardly.

2. A necktie holder comprising a sheet body portion, having a button receiving aperture, an upright slide mounted upon said body below and in vertical alignment with said aperture and adapted to coact with the body to lock the head of a collar button therein, a spring adapted to urge said slide upwardly, and a manually operable pendant pull rod, attached to said slide and extending downwardly, whereby the latter may be withdrawn at will.

3. A necktie holder comprising a sheet metal base plate having lateral wing portions and a central pendant knot portion, a central button receiving aperture in said central base plate portion, vertical guides carried by said base plate below and in vertical alignment with said button receiving aperture, a slide mounted in said guides, an inclined spring member carried at the upper edge of said aperture and formed integrally with said base plate, and a tension spring operatively interposed between said inclined spring member and said slide tending to draw said slide upwardly and lock the head of a collar button inserted between the upper end of said slide and said inclined spring member.

4. A necktie holder comprising a sheet metal base plate having lateral wing portions and a central pendant knot portion, a central button receiving aperture in said central base plate portion, vertical guides carried by said base plate below and in vertical alignment with said button receiving aperture, a slide mounted in said guides, an inclined spring member carried at the upper edge of said aperture and formed integrally with said base plate, a tension spring operatively interposed between said inclined spring member and said slide tending to draw said slide upwardly and lock the head of a collar button inserted between the upper end of said slide and said inclined spring member, and a manually operable pendant pull rod, attached to said slide and extending downwardly, whereby the latter may be withdrawn at will.

Signed at Philadelphia, in the county of Philadelphia, and State of Pennsylvania this 4th day of December, 1926.

ABE JAFFE.
